(57) **CLAIM**

The ornamental design for a breath collection device, as
shown and described.

DESCRIPTION

FIG. 1 is a rear perspective view of a breath collection
device;

FIG. 2 is a front perspective view of the breath collection
apparatus device;

FIG. 3 is a first side view of the breath collection device;
FIG. 4 is a second side view of the breath collection device;
FIG. 5 is a rear view of the breath collection device; and,
FIG. 6 is a front view of the breath collection device.
The broken lines in the drawings depict portions of the
breath collection device that form no part of the claimed
design.
